(57) CLAIM

The ornamental design for a lingerie travel bag, as shown and described.

DESCRIPTION

FIG. 1 is a front, top perspective view of a lingerie travel bag showing my new design;

FIG. 2 is a rear, top perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top plan view of the lingerie travel bag of FIGS. 1-8 shown open and unfolded flat for hanging; and,

FIG. 10 is a bottom plan view of the unfolded lingerie travel bag of FIG. 9.

The broken lines showing portions of the bag are for the purposes of illustrating environment and form no part of the claimed design.
